CYLINDER FOR VALVELESS, TWO-CYCLE, INTERNAL-COMBUSTION MOTORS.

1,105,585.

Specification of Letters Patent.

Patented July 28, 1914.

Application filed April 12, 1913. Serial No. 760,755.

To all whom it may concern:

Be it known that I, CLEMENT E. AMON, citizen of the United States, residing at Franklin, in the county of Venango and State of Pennsylvania, have invented certain new and useful Improvements in Cylinders for Valveless, Two-Cycle, Internal-Combustion Motors, of which the following is a specification.

10 The object, construction and utility of my improved starting-arrangement for valveless, two-cycle, internal-combustion motors, are herein set forth with sufficient clearness to enable those skilled in the art to which it 15 appertains, to make and use the same.

The object of this invention is, to provide such a construction and equipment of the pump-chamber of the so-called valveless type of two-cycle gas and oil engines as will 20 adapt the same to be more easily started than they are as commonly constructed.

One form of my improved starting-arrangement is fully illustrated in the drawings, which form a part hereof, the respective figures of which are as follows:—

Figure 1 is a side elevation of a cylinder of an internal-combustion motor, arranged to be equipped in accordance with my invention. Fig. 2 is a plan of the fuel-pipe which 30 is used for starting-purposes. Fig. 3 shows a cylinder partially in central, longitudinal section, with the piston in substantially the charging position, preparatory to starting the motor. Fig. 4 is a fragment of a cylinder and piston, illustrative of the usual construction and without the application of my 35 invention.

The construction shown in the drawings consists of a cylinder 1 and a piston 2 of 40 uniform diameter throughout its length, which is operable therein. Said cylinder is formed at the front end into a pump-chamber 3 of larger diameter than said piston, closed in any suitable manner, as by a head 45, 4, provided with a stuffing-box 5, through which the piston-rod 6 passes. Cylinder 1 is provided with an air-inlet port 7 which has communication with the interior of the cylinder or pump-chamber, through the port 18 50 and a gas-inlet port 8, through which the charge of fuel enters said pump-chamber 3 as the ports 18 and 8 are uncovered by the piston when it is at the rear or compression end of its stroke, as partially shown at Fig. 55 4. As said piston moves forward, the charge

is compressed in said pump-chamber 3 until the by-pass or transfer-port 9 is uncovered by the rear end of the piston; when the fuel-charge passes to the combustion-chamber 10 of the cylinder, the products of combustion 60 having previously passed out through the exhaust-port 11.

In order to start an engine of this type, as commonly constructed, it is necessary to turn the crank a full revolution by hand, 65 using the fly-wheel as a medium for this purpose. Said necessity arises from the fact that, in order to get a charge of fuel into the pump-chamber, the piston must be positioned at the rear or compression end of its 70 stroke, as indicated in Fig. 4, so that the air and gas ports 18 and 8 will be uncovered, to permit the passage or intake of a fuel charge into the pump-chamber. With the larger sizes of engine, this is a difficult operation, both on account of the compression in 75 the combustion-chamber, and the vacuum in the pump-chamber.

It is the object of this invention to provide cylinder construction for valveless two-cycle 80 engines and an arrangement of fuel-supply for starting-purposes, which will obviate said necessity of turning the crank a full revolution when starting, and will adapt the engine to be started with a rocking movement of the crank and a consequent reciprocating movement of the piston at a point where less than the maximum amount of compression in the combustion-chamber will be caused. I accomplish said object by inserting, directly into the pump-chamber 3, at 12, a fuel-pipe,—Fig. 2—which is provided with an air-supply pipe 13 and a gas-supply-pipe 14, also a check-valve 15, said air and gas-supply pipes being controlled by 95 suitable valves 16 and 17, said check-valve 15 being for the purpose of preventing the escape of the fuel-charge back through this pipe when the charge is compressed in the 100 pump-chamber.

It will now be readily understood that when any backward movement of the piston from the position shown in Fig. 3 takes place, a fuel-mixture will be drawn into the pump-chamber through pipe 12, and thereby the necessity of causing the piston to be positioned at the extreme rear end of its stroke in order to admit fuel to the pump-chamber, is avoided, and when the piston 105 is moved forward to the position shown in 110

Fig. 3, said mixture will be transferred to the explosion-chamber, whereby said explosion-chamber may be easily filled with a fuel-charge by a rocking movement of the 5 crank, and when so filled, a quick, backward movement of the piston, and the consequent compression in the combustion-chamber, will produce suitable conditions for the ignition of the charge, that will start the engine running, and after it is started, the fuel-supply through pipe 12 will be discontinued and the fuel will be taken through the piston-controlled ports 7 and 8, in the usual manner.

On account of the extreme simplicity of 15 the valveless type of the two-cycle gas engines, they are a very desirable power to employ in the oil-fields for pumping wells, since they need much less attention and repair than do engines employing valves; the 20 difficulty of starting them, however, as heretofore constructed, has been a serious objection to them, and has prevented the extensive employment of same which would otherwise have obtained.

25 In the older oil-producing territory such as that in and contiguous to, the territory in which applicant resides, the production of the individual wells is small, hence the operators and producers feel the necessity of 30 keeping the cost of production as low as possible, and for this reason a pumping plant is usually in charge of but one man, and if his engine is a hard one to start, it becomes necessary for him to procure assistance for 35 the sole purpose of starting his engine, and this is especially the case if the engine is of the valveless, two-cycle type. On the other hand, if such engine is equipped in accordance with the construction here shown, the 40 pumper is easily enabled to start same without assistance.

45 Applicant is fully aware that there are various modifications of the valve type of two-cycle engines, such, for instance, as that shown in Letters Patent No. 972,841, issued to C. W. Foster on the 18th day of October, 1910, but this engine being of the valve type, as explained in the specification forming a portion of the said Letters Patent, the fuel-inlet pipes must be supplied with valves, 50 and these cannot be dispensed with at any time during the operation of the engine, hence the construction there shown is hereby specifically disclaimed, since applicant's 55 valve-controlled fuel port is utilized for the sole purpose of starting the engine, and is cut out or dispensed with during the normal

operation of the engine, and all of the fuel then enters the piston-controlled ports 18 and 8.

60

I claim—

1. A cylinder for valveless two-cycle, internal-combustion motors, having a combustion-chamber and a pump-chamber therein in combination with a piston of uniform diameter throughout its length operable within said chambers and adapted to be positioned wholly within said combustion-chamber when at the rearward limit of its stroke and to have a portion only of its forward end 70 positioned within said pump-chamber when at the forward end of its stroke, said pump-chamber being of larger diameter than said piston; there being a fuel-inlet-port passing through the wall of said cylinder and positioned and adapted to be piston-controlled for the admission of fuel to said pump-chamber, also a fuel passage in said cylinder leading from said pump-chamber to said combustion-chamber the opening of said passage into said combustion-chamber being positioned 75 and arranged to be piston-controlled, an auxiliary fuel-inlet leading directly into said pump-chamber, and manually operated valves for controlling the 80 passage of fuel into said auxiliary inlet, for the purpose set forth.

2. A cylinder for valveless two-cycle internal-combustion motors having a combustion-chamber and a pump-chamber therein, 90 in combination with a piston of uniform diameter throughout its length operable within said chambers, said pump-chamber being of larger diameter than said piston, there being a fuel-inlet port passing through the wall of 95 said cylinder positioned and adapted to be piston-controlled for the admission of fuel to said pump-chamber, also a fuel passage in said cylinder leading from said pump-chamber to said combustion chamber, the opening of said passage within said combustion-chamber being positioned and arranged to be piston-controlled, an auxiliary fuel-inlet leading directly into said pump-chamber, and means, other than the piston, for 105 controlling the passage of fuel into said auxiliary inlet.

In testimony whereof I affix my signature in presence of two witnesses.

CLEMENT E. AMON.
